(57) **CLAIM**

I claim the ornamental design for an electronic terminal, as shown and described.

DESCRIPTION

FIG. 1 is a top perspective view of a first embodiment of my new design comprising an electronic terminal;

FIG. 2 is a front view of the electronic terminal of FIG. 1;
FIG. 3 is a back view of the electronic terminal of FIG. 1;
FIG. 4 is a right side view of the electronic terminal of FIG. 1;
FIG. 5 is a left side view of the electronic terminal of FIG. 1;
FIG. 6 is a top view of the electronic terminal of FIG. 1;
FIG. 7 is a bottom side view of the electronic terminal of FIG. 1;

FIG. 8 is a top perspective view of a second embodiment of my new design comprising an electronic terminal;

FIG. 9 is a front view of the electronic terminal of FIG. 8;
FIG. 10 is a back view of the electronic terminal of FIG. 8;
FIG. 11 is a right side view of the electronic terminal of FIG. 8;

FIG. 12 is a left side view of the electronic terminal of FIG. 8;
FIG. 13 is a top view of the electronic terminal of FIG. 8;
FIG. 14 is a bottom side view of the electronic terminal of FIG. 8;

FIG. 15 is a top perspective view of a third embodiment of my new design comprising an electronic terminal;

FIG. 16 is a front view of the electronic terminal of FIG. 15;
FIG. 17 is a back view of the electronic terminal of FIG. 15;
FIG. 18 is a right side view of the electronic terminal of FIG. 15;

FIG. 19 is a left side view of the electronic terminal of FIG. 15;

FIG. 20 is a top view of the electronic terminal of FIG. 15;
and,

FIG. 21 is a bottom side view of the electronic terminal of FIG. 15.

The broken line in the figure drawings is included to show unclaimed environment only and forms no part of the claimed design.
